UNITED STATES PATENT OFFICE.

CHARLES JOHN FISHER, OF NIAGARA FALLS, NEW YORK.

LATHE-CHUCK.

1,253,224.

Specification of Letters Patent. Patented Jan. 15, 1918.

Application filed February 3, 1917. Serial No. 148,866.

To all whom it may concern:

Be it known that I, CHARLES J. FISHER, a citizen of the United States, and a resident of Niagara Falls, in the county of 5 Niagara and State of New York, have invented a new and Improved Lathe-Chuck, of which the following is a full, clear, and exact description.

My invention has for its object to provide 10 a lathe chuck having a jaw which may be readily removed for reversal, or to permit the use of another chuck jaw.

Additional objects of the invention will appear in the following specification in 15 which the preferred form of the invention is disclosed.

In the drawings similar reference characters denote similar parts in all the views, in which—

20 Figure 1 is a side elevation showing a chuck provided with my improvement, parts being broken away to illustrate the construction;

25 Fig. 2 is a fragmentary sectional view of a chuck showing the jaw locked to the anchor block;

Fig. 3 is a view showing the construction 30 of the anchor block, the locking jaw with its stem, the spring, the washer, and the locking barrel, the washer and the locking barrel being illustrated in section; and

Fig. 4 is a plan view of the jaw.

By referring to the drawings, it will be seen that the chuck has a body 5 on which 35 jaws 6 are mounted, each of these jaws 6 being mounted in a manner which I will now describe.

For each jaw, there are two sets of guide- 40 ways 7 and 8, each jaw 6 having guide flanges 9 which extend in the guideways 8, the anchoring blocks 10 having guides 11 which extend in the guideways 7. The jaw 6 is secured to the anchor block 10 by means of an anchor jaw 12 which moves in a recess 13 in the jaw 6. The anchor jaw 12 is provided with teeth 14 which are adapted to mesh with teeth 15 in the anchor block 10. The anchor block 10 also has teeth 16 which mesh with a screw 17 journaled in bearings 50 18 in the body 5. With this construction it will be understood that when the teeth 14 on the locking jaw 12 mesh with the teeth

15 on the anchor block 10, as illustrated in Fig. 2 of the drawings, the jaw 6 will be secured for moving with the anchor block 10, 55 in a manner well understood.

With the lathe chucks now in use there is delay in freeing the jaw for reversal or for the substitution of another jaw, but, as will be seen by referring to Figs. 1 and 2 of the 60 drawings, this is not the case with my construction, since the anchor jaw 12 may be moved so that its teeth 14 will be out of mesh with the teeth 15 by means of the stem 19 which extends from the locking jaw 12 in 65 a guideway 20 in the jaw 6. Pivoted to the end of this stem 19 there is a locking barrel 21 which has a bayonet joint connection 22 with the jaw 6 so that the locking barrel 21 may be pressed downwardly, and with it 70 the stem 19 and the locking jaw 12, and the locking barrel 21 may be rotated so that the bayonet joint 22 will lock the locking barrel 21 in the position illustrated in Fig. 2 of the drawings. The locking barrel 21 is pivoted 75 to the stem 19, as has been stated, a pivotal pin 23 having a head which prevents the movement of the locking barrel 21 away from the stem 19. This locking barrel 21 has notches 24 in which teeth 25 on a locking 80 washer 26 are disposed, the said locking washer 26 extending around the stem 19. This locking washer 26 is engaged by a spring 27 which is disposed around the stem 19, this spring 27 having at one end a locking member 28 which is normally disposed in a recess 29 in the locking washer 26, the spring 27 at its other end having a terminal 85 30 which is disposed in a recess in a shoulder 31 of the guideway 20. By referring to the 90 drawings, it will be seen that the spring 27 presses against the shoulder 31 of the guideway, so that when the bayonet joint 22 is free the spring 27 will serve to raise the locking barrel 21, and with it the stem 19 95 and the anchor jaw 12, to free the teeth on the locking jaw from the teeth 15 on the anchor block 10.

When the locking jaw 12 is freed in the manner described, the jaw 6, together with 100 its anchor jaw 12 may be slid in the guideway 8 so that the jaw 6 may be reversed, or, if desired, another jaw may be introduced.

It will be seen that there is a stop lug 33

on the anchor block 10, which is adapted to be engaged by the anchor jaw 12 to limit the forward movement of the jaw 6.

The locking barrel 21 may be rotated by a key.

Having thus described my invention, I claim as new and desire to secure by Letters Patent;

1. In a lathe chuck, a jaw having a recess and a guideway leading thereto, a screw, an anchor block having a thread meshing with the screw, an anchor jaw movable in the recess and adapted to lock against the anchor block, a stem on the anchor jaw disposed in the guideway, resilient means for holding the stem with the anchor jaw away from the anchor block, and means for holding the stem with the anchor jaw locked to the anchor block against the resiliency of the said means.

2. In a lathe chuck, a jaw having a recess, a screw, an anchor block having a thread meshing in the screw, an anchor jaw movable in the recess and adapted to lock against the anchor block, resilient means for holding the anchor jaw away from the anchor block, and means to hold the anchor jaw in locked position against the resiliency of the said means.

3. In a lathe chuck, a jaw having a recess and a guideway leading thereto, a screw, an anchor block having a thread meshing with the screw, an anchor jaw movable in the recess and adapted to lock against the anchor block, a stem on the anchor jaw disposed in the guideway, there being a shoulder in the guideway, a spring in the guideway, engaging the shoulder, means on the stem beyond the shoulder for engagement by the spring so that the spring may move the anchor jaw away from the anchor block and means for locking the stem with the anchor jaw against the anchor block and against the resiliency of the spring.

4. In a lathe chuck, a jaw having a recess and a guideway leading thereto, a screw, an anchor block having a thread meshing with the screw, an anchor jaw movable in the recess and adapted to lock against the anchor block, a stem on the anchor jaw dis-

posed in the guideway, a locking barrel pivoted to the stem, a bayonet joint for locking the locking barrel to the jaw with the locking jaw in engagement with the anchor block, and resilient means for raising the stem and locking the jaw when the bayonet joint is free.

5. In a lathe chuck, a jaw having a recess and a guideway leading thereto, a screw, an anchor block having a thread meshing with the screw, an anchor jaw movable in the recess and adapted to lock against the anchor block, a stem on the anchor jaw disposed in the guideway, a spring disposed around the stem with an end engaging a shoulder in the recess of the block, a washer on the stem having locking means for engagement by a member of the spring, a locking barrel pivoted to the stem, having a notch in which a tooth on the washer is normally disposed, and a bayonet joint connection between the locking barrel and the jaw for locking the stem with the locking jaw in engagement with the anchor block and against the resiliency of the spring.

6. In a lathe chuck, a body having two guideways, a jaw movable in one of the guideways and having a recess and a guideway leading thereto, a screw journaled in bearings in the body, an anchor block movable in the other guideway and having a thread meshing with the screw, an anchor jaw movable in the recess and adapted to lock against the anchor block, a stem on the anchor jaw disposed in the guideway, a locking barrel pivoted to the stem, a bayonet joint for locking the locking barrel to the jaw with the locking jaw in engagement with the anchor block, and resilient means for raising the stem and the locking jaw when the bayonet joint is freed.

7. In a lathe chuck, a jaw having a recess and a guideway leading thereto, an anchor block, means to advance the anchor block, an anchor jaw movable in the recess and adapted to lock against the anchor block, and means disposed in the guideway in the jaw for operating the anchor jaw.

CHARLES JOHN FISHER.
